UNITED STATES PATENT OFFICE.

GEORGE M. BALL, OF GREEN POINT, BROOKLYN, NEW YORK, ASSIGNOR TO
BALL & JEWELL, OF SAME PLACE.

IMPROVEMENT IN GRATE-BARS.

Specification forming part of Letters Patent No. **154,440**, dated August 25, 1874; application filed
July 30, 1874.

To all whom it may concern:

Be it known that I, GEORGE M. BALL, of Green Point, in the city of Brooklyn, county of Kings and State of New York, have invented an Improvement in Grate-Bars, of which the following is a specification:

My invention relates to certain improvements whereby the bars of a grate may be removed and replaced separately, and whereby, also, each bar may be shaken independently, or the bars may be connected so as to be shaken simultaneously. The invention consists in the combination of a frame and a slotted bar provided with a lever and with rocking bearings for the bar, whereby a longitudinally-reciprocating motion may be imparted to each bar independently of the other bars.

In the accompanying drawing, Figure 1 is a top view of my improved grate-bar. Fig. 2 is a side view. Fig. 3 is a longitudinal vertical section. Fig. 4 is a transverse vertical section.

The frame A is formed with two abutments, *a*, one at each end, which abutments rest upon the bearers for supporting the bars in the furnace. The sides of the frame are curved in concavo-convex form, with the convex edge downward, and the concave edge parallel therewith. Between the curved sides of the frame works the bar proper B, resting on bearers *b*, which are pivoted to said frame, and have their upper ends or edges engaging with notches or depressions *c* in the lower side of the bar B. One of the pivoted bearers *b* extends downward below the pivot, so as to form an oscillating lever, by means of which a reciprocating rectilinear motion may be imparted to the bar B. The bar B has two slots extending for nearly its entire length, and entirely through from top to bottom, thus dividing the fire-surface of the bar into three parts, the lower portions of which are narrower than the upper surface, extending downward in

the form of ribs, and having the lower edges curved in a form nearly parallel with the upper or concave edge of the curved portion of the frame. The sides of the frame A are bent inward for the greater portion of the length thereof, and are provided with projections or ribs *d* on the outer sides, so that the body B rests partly over the side of the frame, and when several bars are placed side by side in a grate the projections or ribs *d* come in contact with each other, and preserve the proper distance between the different bars, which distance is about equal to the width of the slot in the bar.

By the construction and arrangement shown herein the bars may be removed and replaced separately and independently of each other, and each bar may be shaken independently of the others. The lower ends of the levers or elongated bearers *b* are provided with eyes *b*^x, by means of which all the bars in the grate may, if desired, be connected, so as to be shaken simultaneously.

At the ends of the frame A, immediately over the abutments *a*, the metal hangs over the ends of the bar B, and covers them from side to side, so that when the bar is shaken its ends pass under the overhanging portions of the frame, and all dust and ashes which may be on the upper surface near the ends are shaken down and pass through the slots into the ash-box.

What I claim as new, and desire to secure by Letters Patent, is—

In a grate-bar, the combination of the frame A, formed with the abutments *a* and ribs *d*, the slotted bar B, and the rockers *b*, one of which serves as a lever, substantially as and for the purpose shown and described.

GEORGE M. BALL.
